CLAIM

The ornamental design for a packaging for a dental component, as shown and described.

DESCRIPTION

FIG. 1 is a perspective view of a closed packaging for a dental component including a housing according to our new design, and a top lid shown in broken lines; the top lid is shown for illustrative purposes only and forms no part of the claimed designed;

FIG. 2 is a top plan view thereof;

FIG. 3 is a bottom plan view thereof;

FIG. 4 is a front elevational view thereof;

FIG. 5 is a rear elevational view thereof;

FIG. 6 is a left elevational view thereof; and,

FIG. 7 is a right elevational view thereof.

The broken line portion of the figure drawings is included to show unclaimed subject matter only and forms no part of the claimed design.
